UNITED STATES PATENT OFFICE.

WILLIAM F. SHAW, OF BOSTON, MASSACHUSETTS.

APPARATUS FOR HEATING OR COOKING BY GAS.

Specification forming part of Letters Patent No. 16,081, dated November 4, 1856; Reissued May 29, 1860, No. 968.

To all whom it may concern:

Be it known that I, WILLIAM F. SHAW, of Boston, in the county of Suffolk and State of Massachusetts, have invented an Im-
proved Apparatus for Heating or Cooking
by Gas and Air When Commingled and
Burned; and I do hereby declare that the
same is fully described and represented in
the following specification and the accom-
panying drawings, of which—

Figure 1, exhibits a side elevation; and
Fig. 2, a vertical and central section of said
apparatus.

In these drawings, A, denotes an air and
gas burner, it being constructed of a tube or
conductor B, and a perforated or wire gauze
top or disseminator, C. Surrounding the
upper part of the burner is a wire gauze or
perforated tube, D, as represented and de-
scribed in the specification and drawings of
a patent granted to me on February 26th
A. D. 1856.

E, is a tube for leading gas into the tube
B, air being suffered to flow freely into the
lower part of the tube B and with the gas
to ascend toward and pass through the dis-
seminator, the base part, F, of the apparatus
being so constructed as to allow air from
without it to pass freely into it. Surround-
ing the perforated tube, D, of the air and
gas burner is what I term the external air
concentrator, G, which is made like a tunnel
inverted, or somewhat in the shape of a cone
or annular disk, so as to cause the air, that
surrounds the burner or its perforated or
wire gauze chimney, D, to be gathered and
made to pass or be concentrated upon the
external surface of the tube, D, when such
air is caused to rise upward by being rare-
fied by the heat radiated from the burner or
its tube D. The object of said tube D, when
used in connection with a burner of this de-
scription is described in my said patent.

The purpose of my improvement or addi-
tion of the concentrator or guide G is to fa-
cilitate or improve the action of the perfo-
rated tube, D, by bringing into contact with
it a greater amount of air than would natu-
rally strike against it, provided the concen-
trator were removed from it and the air al-
lowed to flow freely up into the surrounding
chamber, H, H, and to pass with the gaseous
products into the oven, I, arranged above
the burner and the case of the chamber, H,

as shown in the drawings. By increasing 55
the amount of air passing against the exter-
nal surface of the tube, D, I increase the
amount that will be drawn into the tube by
the action of the heat; and furthermore I
protect the tube more or less from being in- 60
jured by the action of the flame or heat with-
in it. A further object of the concentrator
is to cause the air flowing through the cham-
ber, H, to be brought as near to the burner
or its tube, D, as possible, in order that such 65
air on its entrance into the oven may be
heated and facilitate the operation of bak-
ing in the oven.

The chamber H, H, is shown as surround-
ed by a flue space, X, X, which communi- 70
cates with the upper part of said chamber by
one or more passages or openings Y, Y, and
has one or more orifices, Z, Z, made through
its bottom. This addition enables the part
of the apparatus that is under the oven to 75
be used for boiling a kettle or for various
other heating purposes after the oven has
been removed from it. When the oven is
used on the chamber H, H, air will pass up
through the flue space X, X, and become 80
heated by contact with the external surface
of said chamber; and flow into said cham-
ber, and thence into the oven and operate
to good advantage. Thus the heat which
would be radiated from the sides of the 85
chamber, H, H, and into the external atmos-
phere is taken up by the inflowing current
of air and returned into the said chamber.

At the top of the chamber, H, and directly
over the burner, A, is a large opening, K, by
which the heated volatile products of com-
bustion of the air and gas are caused to flow
into the oven. I arrange in the oven and
over the air and gas burner and the opening
K, as shown in Fig. 2, a distributing plate 90
or disk L, and the oven I form with a de-
scending back flue, M, for the escape of the
volatile products, they passing out of the
same through openings, N, N, formed
through the lower part of said flue. 100

Having thus described my apparatus,
what I claim therein is as follows:

1. I claim combining with the wire gauze
or perforated tube, D, and the air and gas
burner, A, an air guide or concentrator, G,
applied thereto substantially in manner and
for the purpose hereinafter specified. 105
2. I also claim so combining with the

oven, a back flue extending along one or more of its sides, that the spent heated volatile products within the oven may flow into such flue and thence down around the side or sides of the oven, and out of the bottom or lower part of said flue, as described.

In testimony whereof I have hereunto set

my signature this twenty third day of June
A. D. 1856.

WM. F. SHAW.
